GALVANOMETER

Gifford Hefley, San Antonio, Tex., assignor to
Olive S. Petty, San Antonio, Tex.

Application February 14, 1940, Serial No. 318,926

7 Claims. (Cl. 171—95)

This invention relates to improvements in galvanometers of the so-called string type, in which one or more strings are supported in a magnetic field, whereby on the passage through the string of a pulsating current, the string is caused to vibrate transversely of the direction of the field. An optical system is usually associated with the string or strings, whereby the vibrations may be recorded on a sensitized sheet.

The invention is particularly concerned with string galvanometers of the type in which the string is substantially inextensible, a yielding support being provided to permit flexure and lateral vibration of the string. For example, it is a common expedient to anchor one end of the string to a rigid support, and to connect the other end to a second rigid support through a coil spring, the latter being extended as the string is displaced laterally. While this type of suspension is reasonably satisfactory, it has certain disadvantages which are overcome by means of the present invention.

In the first place, while a coil spring may be described as having a "low rate," in that the restoring force exerted thereby increases very slowly with the increase in elongation of the spring, the rate is not sufficiently low to be ignored in sensitive instruments, for example, galvanometers such as are employed in the recording of seismic impulses in the field of geophysical exploration. Thus as the elongation of a coil spring associated with a galvanometer string increases due to lateral displacement of the string, the restoring force is also increased, and the record of string displacement is therefore not directly proportional to the amplitude of the applied impulses so that distortion of the record results. Again, the change in restoring force exerted by the spring for deflections of the string of different extent results in variation of the natural frequency of the string. Furthermore, surging of the spring is likely to occur, and it occasionally happens that adjacent turns of the spring will directly engage during the reception of signals of high amplitude, causing serious distortion of the record.

A second objection to the use of a coil spring in a string galvanometer is based on the fairly high electrical resistance offered by the spring. This resistance not only induces a loss as the direct result of the resistance offered to the passage of electrical energy, often approximating a 50% loss in the case of copper strings having a resistance of 5 ohms, but an indirect loss occurs as the result of low damping. Thus a string in motion

generates a back E. M. F. which is proportional to the number of lines of flux of induction cut by the string in a unit time. This E. M. F. produces a current tending to damp the string, and the larger the current so produced, the greater the damping for any given E. M. F. It can be shown that the damping current is proportional to $1/R$, where R is the total resistance of the string and spring in series with the external shunts. If, however, the combined resistance of the string and spring is halved, the resistance of the shunt may also be halved, and the same ratio of energy dissipated in the string and in the shunt may be maintained, yet the total resistance in the damping circuit constituting the string and shunt is halved. Hence, the damping will be doubled. By means of the present invention it is possible to reduce the resistance in the spring from about 5 ohms to about .1 ohm; consequently, the damping characteristics of the system may be tremendously improved.

A third objection to the use of the conventional coil spring for suspending a galvanometer string is based on the occurrence in coil springs of objectionable transverse vibration, the natural frequency of vibration of the spring often falling within or close to the range of received impulses. These vibrations may apparently be classified as forced vibrations imposed on a resonant system; regardless of their nature, they are found to be highly objectionable in that they interfere with proper recording of the received signal, and it is therefore quite desirable to employ a spring having a natural frequency which is more remote from the desired signal frequency than is afforded by the conventional coil spring.

It is the object of the instant invention to avoid these various objections to the use of a coil spring by the employment of yielding means of a character such that these difficulties are minimized or completely overcome.

More specifically, it is an object of the invention to replace the usual coil spring in a string galvanometer with a spring which may be regarded as a form of leaf spring, but which is so shaped as to avoid or compensate for the objectionable high rate which is characteristic of leaf springs in general. In the preferred form of the invention, this is accomplished by the use of a flat or leaf spring which is generally heart shaped and which is preferably disposed in the plane of lateral vibration of the spring. It is found that such a spring affords in effect a lever arm or arms of which the length varies with flexure so as nearly or completely to compensate for the

increased restoring force developed on flexure. Because of the relatively short length and increased cross-sectional area of such a spring as compared with an equivalent coil spring, the electrical resistance may be greatly reduced and the natural transverse frequency may be greatly increased, so as to avoid the difficulties inherent in a coil spring resulting from low electrical damping and objectionable transverse vibrations.

Other objects and features of the invention will be apparent from the following description taken in connection with the accompanying drawing in which:

Figure 1 is an elevation showing certain essential elements of the conventional multiple string galvanometer, to which the instant invention is applied;

Figure 2 is an end elevation of the structure shown in Figure 1;

Figure 3 is an enlarged view of certain of the elements shown in Figure 2, including the preferred type of supporting spring;

Figure 4 is a plan view of the elements shown in Figure 1 which provide the magnetic field; and

Figure 5 is a fragmentary sectional view taken substantially on the line 5-5 of Figure 4.

For convenience in describing the invention, reference is made herein to the accompanying drawing illustrating a preferred embodiment thereof, and specific language is employed to describe the same. It will nevertheless be understood that no limitation of the scope of the invention is thereby intended, various modifications and alterations of the illustrated structure being contemplated, such as fall within the spirit of the invention as outlined in the foregoing general description and recited in the appended claims.

The invention has been illustrated as applied to a conventional type of multiple string galvanometer employing a magnet indicated generally at 10 including a core 11, pole pieces 12 and one or more windings 13 surrounding the core, the windings being energized from conductors 15 in which is caused to flow a current for the purpose of establishing a magnetic field between the pole pieces 12. The pole pieces 12 are apertured as indicated at 17 to afford passage therethrough of a light beam projected by a suitable optical system. One or more strings, in this case a considerable number, are supported so as to define a plane perpendicular to the axis of the optical system and to lie between the faces of the pole pieces 12. Thus the strings cast a shadow in the light beam, and these shadows are recorded on a sensitized sheet which is driven at a constant speed past the beam, vibrations of the strings thus producing traces on the sheet which are representative of such displacement. Pulsating current, representative of a series of separately generated impulses which it is desired to record, is applied to each string, and the amplitude of vibration of each string in a plane parallel to the faces of the pole pieces is thus representative of the amplitude of the pulsating current.

The arrangement thus far described is entirely conventional, and no significance is attached to the details thereof. It is contemplated that any equivalent system may be employed in lieu of that shown, the novelty in the instant case residing solely in the method of suspending each of the strings, which is about to be described.

Thus each string is secured at one end thereof,

for example the lower end, to a fixed support 22. Secured to a second fixed support 23 is a plurality of spring elements, one being secured to the adjacent end of each string. These spring elements are of the flat or leaf type and are generally heart shaped as shown more particularly in Figures 2 and 3, as viewed in a direction perpendicular to the plane of vibration of the strings. The convex apex 28 of the spring 30 may be secured directly to the support 23, but is preferably connected thereto by means of a wire or rod 32, which is secured to the support and to the spring, the rod having such rigidity that it does not partake of the vibration imparted to the string. The concave apex 33 of the spring is secured to the string 26. The width of the spring 30, measured transversely of the plane of vibration of the string, and the thickness of the spring, as measured in the plane of vibration of the string, are of course so selected as to apply to the string a restoring force which is sufficient for the purpose of providing a satisfactory record of the received impulses, but it will be appreciated that these dimensions are in general such that the electrical resistance of the spring will be much less than that of a coil spring of adequate restoring force and sufficient in other respects for the intended purpose.

When an electrical impulse is applied to a string so as to induce in the string lateral vibrations, the associated spring 30 will be flexed and will move toward the position shown in dotted lines in Figure 3. In any leaf spring it can be shown that while flexure actually occurs over the entire length of the spring, it may be assumed that the spring flexes about a point intermediate the ends thereof for the purpose of determining the leverage exerted by the spring. While this point may be displaced slightly during flexure, the displacement is not considerable. In the case of the spring disclosed herein, it may be assumed that flexure occurs approximately at the point 35 on each arm of the spring, and the effective leverage exerted by the spring may therefore be measured by the perpendicular distance between this point and the axis of the spring. In other words, we would have an equivalent construction if we provided an articulated system of rigid levers extending between the points 28, 35 and 33, and yieldingly resisted angular displacement of these levers by the provision of torsion springs or the like at one of the points of articulation, for example at the point 35. It will thus be appreciated that as the point 33 moves downward, the effective lever arms, measured by the distance between each of the points 35 and 33, increase with spring flexure. Consequently, although the restoring force also increases on flexure, the increase in restoring force is approximately compensated by the increase in the lever arm, so that the tension applied to the string tending to restore the same to its initial position is approximately constant regardless of the amplitude of displacement of the string. Thus by the use of this type of spring, I have in effect materially reduced the spring rate, and correspondingly lessened the extent of distortion of the record. Furthermore, since the tension applied to the string does not materially vary, I may employ a spring having a relatively large restoring force when in repose.

In the recording of seismic impulses, the natural frequency of the impulses is of a relatively low order. Consequently, it is difficult to design a coil spring which is otherwise satisfactory as

regards restoring force and other characteristics, which is not at the same time characterized by a correspondingly low natural frequency of lateral vibration. It will be appreciated that in general the leaf or flat spring has a much higher natural transverse frequency than an equivalent coil spring, and it can be shown that in the case of the spring illustrated herein, a natural frequency of lateral vibration can be established, which is at least three times that of a coil spring, and the spring is accordingly substantially free from critical vibrational periods. Thus it is possible by use of the spring disclosed herein to avoid undesirable vibrations and consequent blurring of the record line. That the electrical resistance of the present spring may be reduced well below that of an equivalent coil spring is quite apparent, and the advantages inherent in the use of a spring of low electrical resistance have been heretofore outlined.

It will be appreciated from the foregoing that certain features and advantages of the instant invention may be achieved even though the shape of the spring varies to a considerable extent from the preferred shape illustrated herein, and that in its broader aspect the invention is not limited as regards the shape or size of the spring. It will also be understood that changes in the transverse sectional contour of the spring may be effected without materially altering the result. For example, the spring may be formed of round rather than flat stock, and the spring is described herein as a flat or leaf spring merely in order to distinguish over the conventional coil spring, the term being used in a broad sense.

Having thus described the invention, what is claimed as new and desired to be secured by Letters Patent is:

1. In a string galvanometer of the type in which a conducting string is supported for lateral displacement in a magnetic field, supporting means for the string including a spring having the ends thereof disposed substantially in the string axis and having an intermediate portion extending laterally of said axis and beyond said ends as measured in the direction of said axis, said spring ends being secured respectively to the string and to a support so as to increase the spacing between the ends on increase of spring displacement, said spring being so constructed and shaped that the force exerted thereby on said string acts through a lever arm which increases with string displacement.

2. In a string galvanometer of the type in which a conducting string is supported for lateral displacement in a magnetic field, supporting means for the string including a generally heart shaped spring having the apices thereof disposed substantially in the spring axis and connected to the string and a support respectively so as to increase the spacing of the apices on increase of string deflection, said spring being so constructed and shaped that the force exerted thereby on said string acts through a lever arm which increases with string displacement.

3. In a string galvanometer of the type in which a conducting string is supported for lateral displacement in a magnetic field, supporting means

for the string including a generally heart shaped spring having the apices thereof disposed substantially in the spring axis and connected to the string and a support respectively so as to increase the spacing of the apices on increase of string deflection, said spring being initially tensioned to urge said apices toward each other, said spring being so constructed and shaped that the force exerted thereby on said string acts through a lever arm which increases with string displacement.

4. In a string galvanometer of the type in which a conducting string is supported for lateral displacement in a magnetic field, supporting means for the string including a flat spring having the ends thereof disposed in the string axis and connected to the string and a support respectively so as to increase the spacing of the spring ends on increase of the string deflection and having an intermediate bowed portion tensioned to urge said ends toward each other, the bowed portion of said spring extending beyond said ends as measured in the direction of the string length, said spring being so constructed and shaped that the force exerted thereby on said string acts through a lever arm which increases with string displacement.

5. In a string galvanometer of the type in which a conducting string is supported for lateral displacement in a magnetic field, supporting means for the string including a flat spring having the ends thereof disposed in the string axis and connected to the string and a support respectively so as to increase the spacing of the spring ends on increase of the string deflection and having intermediate, similarly shaped bowed portions extending on opposite sides of said axis and beyond said string ends, as measured in the direction of the string length, said spring being so constructed and shaped that the force exerted thereby on said string acts through a lever arm which increases with string displacement.

6. In a string galvanometer of the type in which a conducting string is supported for lateral displacement in a magnetic field, supporting means for the string including a flat spring having the ends thereof disposed in the string axis and connected to the string and a support respectively so as to increase the spacing of the spring ends on increase of the string deflection and having intermediate, similarly shaped bowed portions extending on opposite sides of said axis, said spring being so constructed and shaped that the leverage exerted by said bowed portions increases with string displacement to compensate substantially for increasing spring tension.

7. A spring for use in string galvanometers to apply substantially constant spring tension with varying string displacement, said spring being generally heart shaped and having the apices so connected respectively to the string and to a fixed support as to increase the spacing between said apices on increased string flexure, said spring being so constructed and shaped that the force exerted thereby on said string acts through a lever arm which increases with string displacement.

GIFFORD HEFLEY.
